(57) **CLAIM**

The ornamental design for a pool cover assembly top track, as shown and described.

DESCRIPTION

FIG. 1 is a perspective view of a pool cover assembly top track, showing our new design.

FIG. 2 is a front side view of the pool cover assembly top track of FIG. 1.

FIG. 3 is a rear side view of the pool cover assembly top track of FIG. 1.

FIG. 4 is a left view of the pool cover assembly top track of FIG. 1.

FIG. 5 is a right view of the pool cover assembly top track of FIG. 1.

FIG. 6 is a top view of the pool cover assembly top track of FIG. 1; and,

FIG. 7 is a bottom view of the pool cover assembly top track of FIG. 1.

The evenly dotted broken lines in the figures illustrate features of the pool cover assembly top track that form no part of the claimed design. The dash-dot-dash broken lines in the figures define boundary lines that form no part of the claimed design.
